Filed Nov. 17, 1966, Ser. No. 4,718

Term of patent 14 years

(Cl. D13—6)

Fig. 1.

Fig. 2.

Fig. 3.

FIG. 1 is a perspective view, taken generally from one side and above, of a track member showing my new design, the opposite side being a mirror image of the side shown; and

FIG. 2 is an end elevation of the track member.

FIG. 3 is a perspective view taken from one side and below the track member.

The track member is broken away at one end thereof to indicate an article of indeterminate length.

I claim:

The ornamental design for a track member for folding walls, as shown and described.
